UNITED STATES PATENT OFFICE.

FRANK J. WILKE, OF EAST ST. LOUIS, ILLINOIS.

SPARK-ARRESTER.

SPECIFICATION forming part of Letters Patent No. 740,503, dated October 6, 1903.

Application filed August 29, 1902. Serial No. 121,530. (No model.)

To all whom it may concern:

Be it known that I, FRANK J. WILKE, a citizen of the United States, residing at East St. Louis, in the county of St. Clair and State 5 of Illinois, have invented a new and useful Spark-Arrester, of which the following is a specification.

This invention relates to spark-arresters for locomotives; and it has for its object to 10 provide a device of this class which shall possess superior advantages in point of simplicity, durability, and general efficiency and by the use of which the escape of cinders and sparks shall be effectually prevented.

15 With these ends in view the invention consists in the improved construction, arrangement, and combination of parts, which will be hereinafter fully described, and particularly pointed out in the claims.

20 In the accompanying drawings, Figure 1 is a sectional side elevation showing the front end of a locomotive-boiler to which my invention has been applied. Fig. 2 is a sectional front elevation of the same. Fig. 3 is a sec- 25 tional detail view illustrating a modification.

Corresponding parts in the several figures are indicated by similar numerals of reference.

My invention is applicable to different kinds 30 and constructions of boiler-furnaces; but it is especially useful in connection with the furnaces of locomotive-boilers. Hence its application in such a connection has been illus- 35 trated in the drawings.

35 1 designates the smoke-arch, and 2 the smoke-stack. Below the front end of the casing is disposed a receiving-hopper 3, communicating with the interior of the smoke-chamber through an opening 4. Above said open- 40 ing is disposed a hood or casing 5, which may be rectangular in cross-section and which is provided at what I shall term its "front" end with an elongated S-shaped deflecting-plate 6, the lower end of which is extended slightly 45 through the opening 4 and connected with the edge of a wire screen 7, which is disposed transversely in the receiving-hopper, so as to form a foraminous closure for the part of the opening 4 lying in rear of the deflector rela- 50 tively to the front end of the hood 5. The rear end of the latter is closed by a flange 8,

attached to the lower end of the pipe 9, which extends into the smoke-stack, the said pipe being preferably curved so as to conform to the curvature of that part of the boiler-casing 55 which constitutes the smoke-arch.

10 designates a pipe the lower end of which extends through the boiler-casing and is suitably connected with the exhaust of the engine. Said pipe 10 is tapered from its receiv- 60 ing to its discharge end, and it is curved so as to discharge into the front end of the hood 5, the discharge end of said exhaust-pipe terminating a short distance in front of said box.

The receiving-hopper is provided with a 65 suitably-constructed tilting bottom 11, capable of being operated by means of suitably-disposed levers 12 from the engineer's cab or from any desired point.

In operation the heavier products of com- 70 bustion on entering the smoke-chamber will be drawn by the suction caused by the exhaust-steam passing through the pipe 10 through that part of the opening 4 which is disposed in front of the deflector 6. The 75 lighter particles will rise and enter the stack through the annular space surrounding that end of the pipe 9 which extends into the stack. The heavier particles (cinders and the like) will be restrained from leaving the receiving- 80 hopper by the screen 7, which, however, permits the passage of the lighter and comparatively harmless particles which, with the exhaust-steam, rise through the opening 4 in rear of the deflecting-plate 6 and pass through 85 the pipe 9 into the smoke-stack. It will be observed that the exhaust-steam, although passing through a somewhat-tortuous course, loses little of its power to create a suction or draft in the smoke-stack, while it is vastly 90 useful in separating the heavy and obnoxious from the comparatively innocuous particles of the products of combustion, the former being not only deflected into the receiving-hop- 95 per, but absolutely prevented from leaving the latter by the combined action of the screen 7 and the exhaust-steam constantly entering through the forward portion of the opening 4. Another advantage which should not be lost sight of is that a portion of the exhaust- 100 steam will become condensed, and thus act to extinguish the sparks subjected thereto.

When the hopper is full or at any desired time, it may be emptied by simply manipulating the levers operating the tilting hopper.

I desire it to be understood that while I have described and illustrated what I consider to be the preferred form of my invention I reserve the privilege and right to any changes, modifications, or alterations which may be resorted to without detracting from the utility of my invention or departing from the spirit and scope of my invention.

One modification which I consider to be within the scope of my invention has been illustrated in Fig. 3 of the drawings. In this case the discharge end of the pipe 9, instead of being extended upward into the stack, is connected directly with said stack, leaving no annular opening surrounding the same for the direct escape into the stack of the lighter products of combustion. When this construction is resorted to, it is obvious that all the products of combustion which escape into the smoke-arch must come under the influence of the exhaust-steam discharged through the pipe 10, thus causing all the heavy and gross particles to be deflected and precipitated into the hopper 3, while only such light particles as are capable of passing through the screen 6 will eventually be discharged from the pipe 9 into the smoke-stack.

Having thus described my invention, I claim and desire to secure by Letters Patent of the United States—

1. In a device of the class described, the smoke-chamber having an opening in the bottom thereof, a receiving-hopper disposed below said opening, an open-ended hood disposed above said opening, and a deflector within said hood extending into the said opening intermediately between the ends of the latter.

2. In a device of the class described, the smoke-chamber having an opening in the bot-

tom thereof, a receiving-hopper disposed below said opening, an open-ended hood disposed above said opening, a deflector within said hood extending into said opening intermediately between the ends thereof, means for directing exhaust-steam against said deflector, and a discharge-pipe connecting the rear end of the hood with the smoke-stack.

3. In a device of the character described, the smoke-chamber having an opening in the bottom thereof, a receiving-hopper, disposed below said opening, an open-ended hood above said opening, a deflector disposed within said hood and extending into said opening intermediately between the ends thereof, a screen disposed transversely in the hopper and connected with the lower end of the deflector, means for directing exhaust-steam against the deflector, and discharge means connecting the rear end of the hood with the smoke-stack.

4. A device of the class described, comprising means for discharging exhaust-steam into the smoke-chamber, means for deflecting, precipitating and intercepting the heavier particles of the products of combustion within the primary suctional influence of the exhaust-steam, and tortuous means for conducting the exhaust-steam from the intercepting means to the stack, the discharge-pipe leading into the stack being of smaller diameter than the latter so as to permit the escape through the annular opening thus formed of the lighter products of combustion beyond the range of the primary suctional influence of the exhaust-steam.

In testimony that I claim the foregoing as my own I have hereto affixed my signature in the presence of two witnesses.

FRANK J. WILKE.
